(57) **CLAIM**

The ornamental design for a reader device dock, as shown and described.

DESCRIPTION

FIG. 1 illustrates a front view for a reader device dock. FIG. 2 illustrates a back view for the reader device dock. FIG. 3 illustrates a top view for the reader device dock. FIG. 4 illustrates a side view for the reader device dock. FIG. 5 illustrates a side view for the reader device dock. FIG. 6 illustrates a bottom view for the reader device dock. FIG. 7 illustrates a perspective view for the reader device dock; and, FIG. 8 illustrates a perspective view for the reader device dock.

The broken line showing portions of the reader device dock illustrates unclaimed environment and forms no part of the claimed design. The claimed reader device hub is not intended to be limited to the scale illustrated in the figures.

1 Claim, 8 Drawing Sheets
